CLAIM

The ornamental design for a concealing cover-up with integrated pockets, as shown and described.

DESCRIPTION

FIG. 1 is a front elevation view of a concealing cover-up with integrated pockets showing my new design.

FIG. 2 is a rear elevation view; and,

FIG. 3 is a rear elevation view in an alternate position showing the front view of the pockets with one pocket being in an open position.

The broken line showing of buttons is included for the purpose of illustrating environment and forms no part of the claimed design.

The broken line showing along the edges of the article is included for the purpose of illustrating stitching and is part of the claimed design.
